UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

LOCOMOTIVE.

Application filed September 17, 1921. Serial No. 501,340.

To all whom it may concern:

Be it known that I, WILLIAM W. SLOANE, a citizen of the United States, residing at Chicago, in the county of Cook and State 5 of Illinois, have invented an Improvement in Locomotives, of which the following is a specification.

This invention relates to improvements in mine locomotives and more particularly 10 to mine locomotives having a relatively short wheel base. The object of the invention is to provide means for eliminating excessive periodic movement, or "teetering" of the locomotive frame.

15 As heretofore constructed, locomotives of the class above described, are subject to a tendency to "teeter," or sway forward and backward, while passing over uneven track. This is particularly noticeable in locomotives having a relatively short wheel base, and is largely due to the action of the spring suspension means which allow periodic movements of the locomotive frame when the movement of the springs is unrestricted. 20 This "teetering" is very objectionable, inasmuch as it causes excessive stress on the springs themselves, interferes with the operation of the locomotive, and often has been sufficient to cause the locomotive to be 25 derailed.

The present invention consists, broadly, in providing a locomotive with a device similar to a shock absorber in connection 30 with the spring suspension means. The invention may best be understood by referring to the drawings illustrating one embodiment of my improved device, in which Figure 1 shows a locomotive having my invention applied thereto. Fig. 2 is an enlarged detailed cross-section of the shock absorbing device taken on line 2-2 of Fig. 1. Fig. 3 is a view in elevation of my improved device viewed from the inside of the locomotive frame.

45 Referring now to details of the device, the locomotive frame 1 is provided with a plurality of pedestals 2, of any approved design, each adapted to afford vertical movement of an axle box 3. My improved device is applied to each pedestal, and comprises a pair of vertically disposed rods 4, 50 extending upwardly from the axle box and connected at their lower ends to a plate 5 which rests upon the top of the box. A supporting spring 6 of any preferred pattern

is interposed between the plate 5 and a stirrup 7 formed integral with the pedestal 2 so as to provide a support for the locomotive frame on the axle box in the usual manner. The rods 4, 4, extend upwardly 60 through the stirrup 7 and each is provided at its upper end with a pair of friction blocks 8, 8. These blocks are preferably provided with threads which engage on threaded end portions 4^a of the rods. Each 65 pair of blocks is frictionally engaged between inner and outer clamping plates 9 and 10 respectively, both of which are retained between the stirrup 7 and a projection 13 extending laterally from the top of 70 the pedestal 2. The clamping plates 9 and 10 are held under tension by suitable means such as a rod 12 connected at one end to the outer plate 10 and extending through the inner plate 9, and provided with a shoulder 75 such as a washer 12^a. A spring 11 is interposed between said washer and the inner plate 9 as shown in Fig. 2. The tension on the spring 11 may be regulated by a nut 12^b threaded on the end of the rod 12 and 80 engaging the washer 12^a.

In practice, the tension on the friction blocks is regulated so as to afford substantially normal resiliency of the locomotive suspension means, but the friction is sufficient to check any excessive movements of 85 the locomotive frame.

I claim as my invention:

1. In combination with a locomotive frame having guiding means therefor, an axle box, spring suspension means interposed between said frame and said axle box affording relative vertical movement within said guiding means therebetween, and a friction device independent of said guiding 95 means coacting between said frame and axle box.

2. In combination with a locomotive frame, an axle box, spring suspension means interposed between said frame and said axle 100 box, affording relative vertical movement therebetween, a friction member carried by one of said movable members and a clamping device carried by the other of said movable members, adapted to engage said friction member.

3. In combination with a locomotive frame, an axle box, a pedestal having a stirrup, and a projection above said stirrup, spring means interposed between said box 110

2
and said stirrup, a clamping device interposed between said stirrup and said projection, and means connected with said axle box having frictional engagement with said 5 clamping device.

4. In combination with a locomotive frame, an axle box, a pedestal having a stirrup, and a projection above said stirrup, spring means interposed between said box 10 and said stirrup, a spring pressed clamping device interposed between said stirrup and said projection, and means connected with said axle box having frictional engagement with said clamping device.

15. 5. In combination with a locomotive

frame, an axle box, spring suspension means affording relative vertical movement therebetween, a friction member carried by one of said movable members comprising a threaded rod, and a pair of friction blocks 20 each provided with a semi-circular groove threaded to engage opposite sides of said rod, and a clamping device carried by the other of said movable members adapted to engage the outer faces of said friction blocks. 25

Signed at Chicago, in the county of Cook and State of Illinois, this 14th day of September, 1921.

WILLIAM. W. SLOANE.
